APPARATUS FOR ETHER ANESTHESIA

Francesco d'Agostino, Imola, Italy

Application December 1, 1937, Serial No. 177,632
In Italy December 12, 1936

9 Claims. (Cl. 128—192)

My invention relates to a new apparatus for ether anesthesia allowing the formation of a substantially perfect mixture which is continually proportioned according to the surgeon's intentions and consists in overheated ether fumes combined with air and anhydrous carbonic acid breathed out by the patient.

The constructional features and the operation of the apparatus according to my invention may be understood by reference to the following description taken in connection with the accompanying somewhat diagrammatical drawings.

Fig. 1 represents a first form of carrying out my present invention.

Fig. 2 represents a second form of the apparatus according to my invention.

Fig. 3 shows a sectional view of a drip-cock adapted for use in the apparatus.

Fig. 4 shows a sectional view of a double valve operating in two directions without springs and to be used with the apparatus.

The apparatus represented in Figure 1 consists in a boiler 1 containing water, which is heated by means of an electric resistance 2, or by any other suitable means; the temperature of the water is indicated by a thermometer 3. The main member of the apparatus is located in the boiler 1 that is to say a receiver 4 divided in two compartments 4' and 4'' separated from each other by a diaphragm 5 which contacts at its lower edge a gauze-net 6, extending to the walls of the receiver. Below this net the receiver is extended so as to form a funnel ending with the pipe 7 in the water-vat 8. The wool cotton that absorbs the ether is placed in the two compartments 4' and 4'' of the receiver 4. Several pipes 10 and 10' connect the two compartments 4' and 4'' and the two chambers 11 and 11' respectively. From these two chambers the pipes 12 and 12' lead outside through the cover of the boiler 1. The pipe 12 is provided with a valve 13 and an extensible bladder 14 from which a flexible tube 15 leads to the mask 16, a suitable valve 17 being provided at the joining point. The other pipe 12' also leads by a flexible tube 15' having a valve 17' to the mask 16. A graduated ether flask 18 with a drip-cock 19 communicates with the receiver 4 by means of the vertical pipe 20 directly above the diaphragm 5.

The pipe 7 is closed at the bottom and is provided with several lateral holes 9 through which the water of the container 8 may enter into the interior of the pipe 7 where it will be evaporated under the action of the electrical resistance 2.

The operation of the apparatus is as follows:

When the patient to which the mask is applied breathes out, the valve 17 will be opened, whereas the valves 17' and 13 remain closed, the bladder 14 will be inflated and receive the expired air. When afterwards the patient breathes in, the valve 17 will be closed and the valve 17' and 13 will be opened. The bladder 14 will release its content of anhydrous carbonic acid (expired air) to the tube 12, where it is mixed with fresh air which enters through the open valve 13 and passes through the chamber 11 and the pipes 10 to the receiver 4 which contains wool cotton impregnated with ether by the continuous regulated supply from the drip-cock 19. The mixture is compelled by the inspiration of the patient to descend through the first compartment 4', to pass through the net 6 in the lower free space of the receiver 4 and to rise then through the second compartment 4'', the pipes 10' and the chamber 11' to the flexible inhalation tube 15' reaching at last the mask 16 through the open valve 17'. Thus the patient inspires a mixture of anhydrous carbonic acid (from the bladder 14), of fresh air (from the valve 13), and of overheated ether fumes (from the receiver compartments 4' and 4''). The mixture contains also a certain degree of moisture collected from the water-vat 8 warmed by a tube 7, and vapour formed therein is aspirated by the described current of the mixture towards the net in the receiver 4 and mixes with the said current.

In the form of my apparatus shown in Fig. 2, the boiler 1 is externally like the boiler according to Fig. 1, but besides the electric resistance 2 in the bottom, other heating resistances 22 are provided in the middle of the boiler in order to heat the pipes 23, 24, leading from the two chambers 26 and 27 to the mixing chamber 28 and in order to heat furthermore the pipe 25 through which the ether drops are falling to the chamber 27. In this chamber a first mixing of ether fumes with air and vapour is obtained by its being in connection with the valve 30, through the pipe 29 and with the water vat 31 through the pipe 32. The water vat 31 is as shown tightly closed and the water therein is slowly heated due to the thermic conductivity of the pipe 32. The water vapor therefore which is formed escapes through the pipe 32 and enters the mixing receptacle 27. The mask for the patient is not shown in this figure, but only the inhalation pipe 36 and the exhalation pipe 35 with the extensible bladder 33 and the valve 34 having the same functions as the analogous members 12—14 of the Fig. 1. The manner in which the

different elements of the anesthetic mixture are mixed with each other are somewhat different in this second constructional form. The anhydrous carbonic acid which was collected in the extensible bladder 33 during the breathing out phase, is released during the breathing in phase and mixed with fresh air in the chamber 26 from which, always under the effect of the partial vacuum, which in this latter phase is acting through the pipe 36 in the mixing chamber 28, it will be aspirated through the pipe 23, where it is warmed by the resistance 22 and finally mixed with the other elements of the mixture in the chamber 28. These other elements, such as ether, moisture and fresh air, before reaching the mixing chamber 28 are premixed in the chamber 27 connected by the pipe 29 with the air valve 30, by the pipe 32 with the water-vat 31 and by the pipe 25 with the graduated ether-flask 38. The top end 37 of the pipe 25 is enlarged and has a glass window to observe the effect of the manual regulation of the ether by the drip-cock 39. This drip-cock, as shown in section in Figure 3, is characterised by the Z-form of the inner channel 40 and by the lateral penetration of the conical point of the needle 41 in the said channel for the purpose of regulation.

Fig. 4 shows a form of a double-acting valve which is in connection with the patient's mask by means of the pipe 42 in which the current of breath passes in the two directions, respectively opening and closing the two valves 43 and 44 which have no springs and in the state of rest are both closed only by gravity. The valve 43 is opened by the breathing out current and the valve 44 is opened by the breathing in current.

This form of execution of the apparatus has the advantage of securing a greater individual regulation of the temperature for the several elements forming the anesthetic mixture. It is to be understood that the constructional elements may change and that parts may be omitted, as for instance, the water vats 8, 31 since moisture may be obtained also from the hot water contained in the boiler 1.

The advantages of both forms of execution compared with the known type of apparatus for ether anesthesia are the following:

- (1) No initial sensation of suffocation for the patient;
- (2) A very efficient pulmonary ventilation is assured without applying to the volitive faculties of the patient;
- (3) Absence of any irritation of the respiratory ways;
- (4) Absence of a period of excitation of the patient;
- (5) The complete anesthesia is obtained in less time;
- (6) Perfect releasing of abdominal walls;
- (7) Presence of the reflexes during the anesthesia proving the absence of the poisonous effect on the bulbar centres;
- (8) Rapid awakening without vomiting;
- (9) Possibility of controlling the conditions of the patient as his respiration is visible with the movements of the extensible bladder;
- (10) Utilization of an autogen gas (anhydrous carbonic acid) for the physiological excitation of the bulbar centres;
- (11) Possibility to use the apparatus after the closure of the ether supply for facilitating the awakening by means of the excitation of the bulbar centres by the anhydrous carbonic acid breathed out;

(12) Consequent abolition of the bulbar complications (heart, respiration), pulmonary and cardial accidents (inflammation of the lungs, cardial paralyses, etc.);

(13) Simplicity of use;

(14) Economy of ether.

What I claim is:

1. In an apparatus for ether anesthesia, the combination of a container adapted to contain water forming a water bath, means for heating said water, a receptacle located in said bath for the evaporation of ether, means supplying controlled quantities of ether to said receptacle, means for supplying fresh air to said receptacle, means for supplying exhaled air to said receptacle, means for supplying moisture to said receptacle whereby said ether vapor, fresh air, exhaled air and moisture may be mixed in said receptacle, a mask for a patient and exhalation and inhalation connections between said mask and said receptacle.

2. In an apparatus for ether anesthesia, the combination of a container adapted to contain water forming a water bath, means for heating said water bath, means for mixing ether vapor, fresh air, exhaled air and moisture located in said water bath and means for supplying said mixture to a patient.

3. In an apparatus for ether anesthesia, the combination of a container adapted to contain water forming a water bath, means for heating said water bath, means having an inlet and an outlet end located in said water bath for mixing ether vapor, exhaled air, fresh air and moisture, a mask for the patient, means connecting said mask to the inlet end of said mixing means, means connecting said mask to the outlet end of said mixing means and means automatically connecting the patient to either the inlet or the outlet of said mixing means dependent upon whether said patient is exhaling or inhaling.

4. In an apparatus for ether anesthesia, the combination of a container adapted to contain water forming a water bath, means for heating said water bath, means having an inlet end and an outlet end located in said water bath for mixing ether vapor, exhaled air, fresh air and moisture, a mask for the patient, means connecting said mask to the inlet end of said mixing means, means connecting said mask to the outlet end of said mixing means and means automatically connecting the patient to either the inlet or the outlet end of said mixing means dependent upon whether said patient is exhaling or inhaling and means controlling the quantity of ether vapor.

5. In an apparatus for ether anesthesia, the combination of a container adapted to contain water forming a water bath, means for heating said water, a receptacle located in said water bath having an inlet compartment and an outlet compartment, a mask for a patient, means connecting said mask to said inlet compartment, a valve in said last named means communicating with the atmosphere, a bladder also in said last named means for storing exhaled air, means for supplying ether to said receptacle in regulated quantities in order to be vaporized, means for supplying moisture to said receptacle and means connecting said mask with said outlet compartment.

6. In an apparatus for ether anesthesia, the combination of a container adapted to contain water forming a water bath, means for heating said water, a receptacle located in said water bath having an inlet compartment and an outlet com-

partment, a mask for a patient, means connecting said mask to said inlet compartment, a valve in said last named means communicating with the atmosphere, a bladder also in said last named means for storing exhaled air, means for supplying ether to said receptacle in regulated quantities in order to be vaporized, means for supplying moisture to said receptacle and means connecting said mask with said outlet compartment and valve means controlling said means connecting said mask to said inlet and outlet compartments.

7. In an apparatus for ether anesthesia, the combination comprising a container adapted to contain water forming a water bath, means for heating said water, a receptacle located in said bath for the evaporation of ether, means supplying controlled quantities of ether to said receptacle, means for supplying fresh air to said receptacle, means for supplying exhaled air to said receptacle, means for supplying moisture to said receptacle whereby a mixture of ether vapor, fresh air, exhaled air and moisture may be mixed in said receptacle, a mask for a patient, exhalation and inhalation connections between said mask and said receptacle, said means for supplying fresh air including a conduit in said

water bath whereby said air is heated and said inhalation connection including a conduit in said water bath whereby said mixture may be heated.

8. In an apparatus for ether anesthesia, the combination comprising a container adapted to contain water forming a water bath, means for heating said water bath, means for mixing ether vapor, fresh air, exhaled air and moisture located in said water bath, means for supplying said mixture to a patient, means for heating said fresh air by said water bath prior to the mixing of said fresh air with said ether vapor and means for heating said mixture by said water bath before supplying said mixture to a patient.

9. In an apparatus for ether anesthesia, the combination comprising a container adapted to contain water forming a water bath, means for heating said water bath, means for mixing ether vapor, fresh air, exhaled air and moisture located in said water bath, means for supplying said mixture to a patient, means for heating said fresh air and exhaled air by said water bath prior to the mixing of said fresh air with said ether vapor and means for heating said mixture by said water bath before supplying said mixture to a patient.

FRANCESCO D'AGOSTINO.
